DISPLAY DEVICE

Saul H. Chazan, Rochester, N. Y.

Application September 16, 1932, Serial No. 633,484

16 Claims. (Cl. 211—1.5)

The object of this invention is to provide a fashion display device and sign to be used in store windows.

Another object of the invention is to provide a device in which dresses or coats can be displayed on models that will move across an opening therein.

Another object of the invention is to provide descriptive signs that will automatically be displayed as each model appears at the opening.

These and other objects of the invention will be illustrated in the drawings, described in the specification and pointed out in the claims at the end thereof.

In the drawings:

Figure 1 is a front elevation of the device.

Figure 2 is a top plan view of the device shown in Figure 1.

Figure 3 is a top plan view of the machine with the plate and curtain or partition shown in Figure 2 removed, the mechanism for moving the cards being omitted.

Figure 4 is a vertical section on the line 4x—4x of Figures 2 and 3, looking at it from the rear.

Figure 5 is a detail view of the conveyer platform.

Figure 6 is a sectional elevation on the line 6x—6x of Figures 2 and 3, showing one of the conveyer platforms in place in the socket that carries it.

Figure 7 is a vertical section through the tubular supporting frame on the line 7x—7x of Figure 3, showing connections between sections of the frame.

Figure 8 is a horizontal section through the tubular track, showing the connections between sections of the track.

Figure 9 is a perspective detail view of one of the card carriers.

Figure 10 is a detail view of the guide frame in which the card carrier is moved.

Figure 11 is a detail view of one of the chain conveyers for moving the card carriers.

Figure 12 is a vertical section through one of the conveyer platforms, showing the endless chain and the arm and its rolling contact with the track.

In the drawings like reference numerals indicate like parts.

In the drawings reference numeral 1 indicates the front of my device having a large window 2 in the middle thereof, and the small windows 3 and 4 on either side thereof. Behind this front or screen is placed the operating apparatus

shown in Figures 2, 3 and 4. As shown in Figures 2 and 3, the operating device is driven by a motor 5 having a small pulley 6, a belt 7, and a large pulley 8 for the purpose of reducing the angular velocity. The pulley 8 is carried on a shaft 9, which has a worm thereon which drives the worm gear 10 carried on an upright shaft 11. At the top of the shaft 11 is a sprocket wheel 12 driving an endless chain 13, the other end of which chain travels around a sprocket wheel 14 carried on a shaft 15. The shafts 11 and 15 are carried in rectangular frames 16 and 17, in which bearings are provided at the top and bottom in which the shafts 11 and 15 rotate. These rectangular frames are attached to a plank or base 22.

A tubular frame 18 is provided having the intermediate section 18a and the two end sections 18b and 18c which are coupled together by a sleeve 18d. This sleeve has an annular shoulder 18e centrally thereof, and the sleeves 18a and 18c telescope over the sleeve 18d and abut against the shoulder 18e. The sleeve 18d is fastened to the tube 18a by rivets as indicated at 19, and to the sleeve 18c by pins 20. By withdrawing the pin 20, the end section of the tubular frame can be removed from the intermediate section. The frame is coupled together in the same way on both ends.

The pin 20 is fastened to the intermediate section 18a by a chain 21, so that it will always be in place and available, when the frame is taken apart or when it is set up.

Each of the end sections 18b and 18c is provided with a plate extension 25 and 26. This plate extension in each case extends beyond the shafts 11 and 15 and is perforated with a hole through which the shaft can pass and in which it can rotate. The end section 26 is provided with a slot 26a which permits the shaft 15 to be adjusted lengthwise of the frame. An endwise adjustment is provided between the base 22 and the rectangular frame 17.

Intermediate the rectangular frames 16 and 17 I provide the inverted U-shaped frames 27, 28, 29 and 30. These frames have their legs turned in at the bottom as indicated at 31, 31, as shown in Figures 2 and 4, which inturned ends serve as feet.

In this apparatus is also provided the oval tubular track 35, which is shown in section in Figure 8. It consists of one or more straight intermediate sections 35a, together with the U-shaped end sections 35b and 35c. The end sections are fastened to the intermediate sections by sleeves 35d.

which have annular flanges 35e intermediate the ends thereof. The sections telescope over the ends of this sleeve and abut against the flange. The intermediate sections are riveted as indicated at 37, and the end section is fastened with a pin or bolt as indicated at 38.

On the sprocket chain 13 are fastened arms 40, which travel with the sprocket chain. On the outer end of each of these arms 40 is carried a sleeve 41, in which is carried a socket 42. Across this socket 42 is provided a pin 43, at a suitable height. In this socket engages a pin 44, the lower end of which is cut away as indicated in Figures 5 and 6, so that the stem can engage with the socket only in one position. On the stem 44 is carried a rotating platform 45, on which is mounted the figure 46, on which a dress or a coat is to be displayed. On the bottom of the socket 42 is fastened a gear wheel 47, which engages with the stationary rack 48 for the purpose of rotating the platform and figure, as will presently be more fully described.

It will be understood that the sleeve 41 is stationary and that the socket 42 and gear 47 rotate. A ball 49 is provided pressed upwardly by a spring (see Figure 6), which serves to arrest the rotation of the gear socket and model at a suitable point and hold it against further rotation after the gear has disengaged itself from the rack 48.

As above described, the chain 13 has the arms 40 attached thereto and moves these arms around the track 35. Each arm is provided with lugs 50, between which is carried an antifriction roller 51 which rests on and travels on the track, so that the movement of the chain and figures is secured with the least resistance.

At each end of the apparatus I provide a device for displaying cards, printed with suitable legends that are appropriate to the figure that is being displayed in the central opening. It will be understood that as the chain 13 moves, it will convey the platforms 45 and their operating mechanisms successively before the opening 2, and as each one moves across the opening the gear 47 on the bottom thereof will engage the stationary rack 48 and cause the figure to turn once or more times around, so as to display the dress or coat on the model, and while this display is being made, suitable cards which describe the dress or coat et cetera will appear in the openings 3 and 4, and the apparatus by which these cards are displayed will now be described. This card display apparatus is the same at each end of the machine, and a description of one of them will serve for the other.

On the bottom of the shaft 15 is a sprocket gear 60, which drives a chain 61, which in turn drives a sprocket gear 62 on an upright shaft 63 carried in a suitable bearing bracket 64. On the upper end of this shaft is carried the bevel-gear 65, which drives a bevel-gear 66 carried on the shaft 67. This shaft is provided with sprockets 68, 69 which drive sprocket chains 69 at each end thereof, which chains pass over sprockets 70 at the top carried on pins 71 and 72 at each side of the frame, it being understood that the sprockets 70 are not carried on a shaft which runs across between them, but an open space is left between the sprockets for the travel of the cards which are displayed by this device.

On each sprocket chain 69, 68 is carried a pin 75 by which the card holders or carriers 76 are lifted successively and carried around. These pins 75 are opposite each other, as shown at the top of Figure 4.

As shown in Figure 9, I provide a shaft 80 having U-shaped sockets 81 on each end thereof. The card carriers 76, shaft 80 and sockets 81 are rigidly fastened together. One of these card carriers 76 with its sockets always stands in the path of travel of the pins 75, 75. The chain 69 moves up at the right in Figure 11, and the chains 69 are placed on either side of the window 3. The pins 75 engage with the sockets 81, and lifts the card holder up and carries it to the top of movement of the chain 69, and brings it down at the back of the other card holders. It will be understood that a series of these card holders are carried in the frame, one side of which is shown in Figure 10, in which 83 indicates a front plate 15 having side plates 84 thereon on which are carried the blocks 85 and 86, which between them form a cam-shaped slot 87 in which engages the sleeves 88, 88 of the card carrier. There are the same number of card carriers and cards as there are 20 models on the endless chain.

In this way by the movement of the endless chain 69, the front card holder is always drawn out and up, and the next card holder moves forward by gravity into its place in front of the window 3 or 4, so that the legend thereon will describe the figure in the opening 2 as the one figure follows the other.

It will also be understood that the lamps 90 and 91 are placed behind the screen or front 1 of the device, by which the three openings, and the cards and figures displayed therein, are illuminated from behind.

It will also be understood that a curtain 95 is provided back of the window 2. The figures pass 35 between the window 2 and this curtain. The curtain shuts off any view of the rear part of the device, including the platforms and figures.

I claim:

1. In a display device the combination of a 40 tubular frame having an intermediate tubular section, end tubular sections, sleeves connecting said sections, each of said sleeves having a flange thereon extending only to the outside diameter of said tubular sections intermediate the ends 45 thereof against which the sections abut, the outer ends of the end sections being flattened, upright shafts mounted to turn in the end sections, rectangular frames supporting the end sections, means for rotating said shafts in said end sections.

2. In a display device the combination of a tubular frame having an intermediate tubular section, end tubular sections, sleeves connecting said sections, each of said sleeves having a flange 55 thereon extending only to the outside diameter of said tubular sections intermediate the ends thereof against which the sections abut, the outer ends of the end sections being flattened, upright 60 shafts mounted to turn in the end sections, rectangular frames supporting the end sections, means for rotating said shafts in said end sections, sprocket wheels on said shafts, an endless chain traveling between said wheels.

3. In a display device the combination of a tubular frame having an intermediate tubular section, end tubular sections, sleeves connecting said sections, each of said sleeves having a flange 70 thereon extending only to the outside diameter 70 of said tubular sections intermediate the ends thereof against which the sections abut, the outer ends of the end sections being flattened, rectangular frames supporting the flattened part 75 of the end sections and inverted U-shaped frames 75

- supporting the intermediate portions of the frame.
4. In a display device, an elongated frame, sprocket wheels mounted to turn at each end thereof, an endless chain traveling between said sprocket wheels, arms fastened to said chain and extending forwardly and outwardly therefrom, an endless track on which the outer ends of said arms slide, a platform carried on the outer ends 10 of each of said arms a sleeve on the outer end of each of said arms extending below the arm.
5. In a display device the combination of an endless chain, arms carried on said chain, a sleeve supported by each of said arms, a socketed member mounted to rotate in said sleeve, a gear wheel carried on the bottom of said socketed member, a stationary rack with which said gear wheel engages as the chain travels by said rack to rotate said gear and socketed member.
6. In a display device the combination of an endless chain, arms carried on said chain, a sleeve supported by each of said arms, a socketed member mounted to rotate in said sleeve, a gear wheel carried on the bottom of said socketed member, a stationary rack with which said gear wheel engages as the chain travels by said rack to rotate said gear and socketed member, a platform and a pin supporting said platform, said pin positively engaging with said socketed member and rotating therewith.
7. In a display device, the combination of a sleeve and means to support the sleeve, a socketed member mounted to rotate in said sleeve, a gear wheel carried on the bottom of said socketed member, an upwardly spring pressed ball carried on the gear, a recess in said sleeve in which said ball is adapted to engage and stop the gear and socketed member from rotating at a predetermined time.
8. In a display device, the combination of a sleeve and means to support the sleeve, a socketed member mounted to rotate in said sleeve, a gear wheel carried on the bottom of said socketed member, an upwardly spring pressed ball carried on the gear, a recess in said sleeve in which said ball is adapted to engage and stop the gear and socketed member from rotating at a predetermined time, a platform, and a pin supporting said platform, said pin positively engaging in said socketed member at a predetermined angular relation with the spring pressed ball and recess.
9. In a display device, an elongated frame, sprocket wheels mounted to turn at each end thereof, an endless chain traveling between said sprocket wheels, arms fastened to said chain and extending forwardly and outwardly therefrom, an endless track on which the outer ends of said arms slide, lugs on said arm, a pin passing 60 through said lugs, a grooved antifriction roller mounted on said pin between said lugs, said roller being adapted to engage said endless track.
10. In a display device, the combination of an endless tubular frame having straight intermediate tubular sections parallel to each other, a U-shaped tubular section at each end of the frame, sleeves connecting said sections, each of said sleeves having a flange thereon extending only to the outside diameter of the said tubular sections, said flanges being intermediate the ends of the sleeves and against which the ends of the sections abut, pins passing horizontally through the ends of the sections and through the sleeves to hold the parts together, the top of the frame being left smooth and continuous for use as a track.
11. In a display device, the combination of an endless frame having straight intermediate sections parallel to each other, U-shaped sections at the ends of said intermediate sections, means located below the top of said sections for fastening said U-shaped sections to said intermediate sections leaving the top of said endless frame smooth and continuous for use as a track, rectangular frames at each end of said endless frame, by which said endless frame is supported, shafts mounted in said rectangular frames, means for rotating said shafts in said rectangular frames.
12. In a display device, the combination of an endless frame having straight intermediate sections parallel to each other, U-shaped sections at the ends of said intermediate sections, means located below the top of said sections for fastening said U-shaped sections to said intermediate sections leaving the top of said endless frame smooth and continuous for use as a track, rectangular frames at each end of said endless frame, by which said endless frame is supported, shafts mounted in said rectangular frames, means for rotating said shafts in said rectangular frames, sprocket wheels on said shafts, an endless chain engaging said sprockets and adapted to travel between said sprocket wheels.
13. In a display device, the combination of an endless frame having straight intermediate sections parallel to each other, U-shaped sections at the ends of said intermediate sections, means located below the top of said sections for fastening said U-shaped sections to said intermediate sections leaving the top of said endless frame smooth and continuous for use as a track, rectangular frames at each end of said endless frame, by which said endless frame is supported, shafts mounted in said rectangular frames, means for rotating said shafts in said rectangular frames, sprocket wheels on said shafts, an endless chain engaging said sprockets and adapted to travel between said sprocket wheels.
14. In a display device, the combination of an endless frame having straight intermediate sections parallel to each other, U-shaped sections at the ends of said intermediate sections, means located below the top of said sections for fastening said U-shaped sections to said intermediate sections leaving the top of said endless frame smooth and continuous for use as a track, rectangular frames at each end of said endless frame, by which said endless frame is supported, shafts mounted in said rectangular frames, means for rotating said shafts in said rectangular frames, sprocket wheels on said shafts, an endless chain engaging said sprockets and adapted to travel between said sprocket wheels, arms fastened to said chain and extending outwardly therefrom, the outer ends of said arms being adapted to slide on said endless frame.
15. In a display device the combination of an endless frame, rectangular frames at each end of said endless frame by which said endless frame is supported, sprocket wheels mounted to rotate above said rectangular frame, an endless chain engaging said sprockets and adapted to travel between said sprocket wheels, arms fastened to said

chain and extending outwardly therefrom, a platform carried on the outer ends of each of said arms, a figure on each of said platforms, means for rotating said platform and figure one at a time independently of said arms.

16. In a display device the combination of an endless frame, rectangular frames at each end of said endless frames by which said endless frame is supported, sprocket wheels mounted to 10 rotate above said rectangular frame, an endless chain engaging said sprockets and adapted to

travel between said sprocket wheels, arms fastened to said chain and extending outwardly therefrom, a platform carried on the outer ends of each of said arms, a figure on each of said platforms, means for rotating said platform and figure one at a time independently of said arms, and means for holding said platforms and figures in a predetermined position when disengaged from said rotating means. 5
